U.S. Appl. No. 29/533,833, filed Jul. 22, 2015, Solomon.

Primary Examiner — Austin Murphy(74) *Attorney, Agent, or Firm* — Rutan & Tucker, LLP

(57)

CLAIM

The ornamental design for a cable, as shown and described.

DESCRIPTION

FIG. 1 is an elevational view of a left side of a cable according to our new design;
 FIG. 2 is an elevational view of a front side of the cable;
 FIG. 3 is an elevational view of a back side of the cable;
 FIG. 4 is an elevational view of a right side of the cable;
 FIG. 5 is an end view of one end of the cable; and,
 FIG. 6 is an end view of an opposite end of the cable.
 The broken lines showing in FIGS. 1 through 6 are for illustrative purposes only and form no part of the claimed design.

1 Claim, 2 Drawing Sheets---
